UNITED STATES PATENT OFFICE

163,731

RADIO-PHONOGRAPH CABINET PANEL

Samuel E. Adler, Chicago, Ill., assignor to Admiral Corporation, Chicago, Ill., a corporation of Delaware

Application January 6, 1951, Serial No. 13,697

Term of patent 14 years

(CL. D56—4)

To all whom it may concern:

Be it known that I, Samuel E. Adler, a citizen of the United States, residing at Chicago, in the county of Cook, State of Illinois, have invented a new, original, and ornamental Design for a Radio-Phonograph Cabinet Panel, of which the following is a specification, reference being had to the accompanying drawings, forming part thereof.

Fig. 1 is a front elevational view of a radio-phonograph cabinet panel, showing my new design;

Fig. 2 is also an elevational view of the left side thereof;

Fig. 3 is a fragmentary sectional view taken on line 3—3 of Fig. 1, and drawn to an enlarged scale;

Fig. 4 is a fragmentary front elevational view of the lower left-hand corner shown in Fig. 1 but drawn to an enlarged scale;

Fig. 5 is a sectional view taken on line 5—5 of Fig. 1; and

Fig. 6 is a fragmentary rear elevational view of the lower right-hand corner, drawn to an enlarged scale.

I claim:

The ornamental design for a radio-phonograph cabinet panel, as shown.

SAMUEL E. ADLER.
